TO AUTOMATIC SPRINKLER COMPANY OF AMERICA, OF CLEVELAND, OHIO, A COR-
PORATION OF DELAWARE

AUTOMATIC THERMAL VALVE ACTUATOR

Application filed February 7, 1927. Serial No. 166,294.

Our present invention relates to that kind of fire extinguishing systems in which the opening of a valve by the melting of a fuse or similar slow acting thermostat and frequently termed a sprinkler head is the means for controlling or causing the opening of the main valve admitting water or other fire extinguishing medium to the distributing piping to which the sprinkler head is attached. 10 The invention is particularly useful in connection with a system wherein the opening of the main valve is due to release of pressure in the distributing piping thus relieving the main valve of a pressure tending to hold it closed. A well known form of apparatus 15 acting on this principle is called a dry pipe system. The invention relates particularly to means for quickening the action of the apparatus in supplying the fire extinguishing medium at the outlet or outlets forming the sprinkler heads when fire occurs in the premises protected. The invention will be described in connection with a dry pipe system having pressure of air in the distributing 20 piping. In the usual dry pipe system an air pressure is carried in the piping system, the purpose of which is to keep the main dry pipe valve between the source of fluid supply and the piping in its closed position. This air 25 pressure is relieved through the opening of a sprinkler head or other device from the heat of fire. When this occurs air escapes and the air pressure diminishes to a predetermined pressure point at which the dry pipe valve 30 will automatically operate and deliver water or other fire extinguishing medium to the piping and to the sprinkler head opened by the fire. In systems of considerable size there 35 is an undesirable delay due to the time necessary to diminish air pressure sufficient to operate the valve which in some cases amounts to several minutes, during which time the fire continues to grow in magnitude and in some cases is actually fanned by the air issuing 40 from the sprinkler head. One of the pur-

poses of our present invention is to reduce this period of delay by a combination of devices termed by us an automatic thermal valve actuator functioning to cause the dry pipe valve to act before the sprinkler head 35 operates and by the heat of a fire which if allowed to increase will eventually open the sprinkler head and the system operate as above described. Another purpose of our invention is to provide for the giving of an 40 alarm or signal in connection with the operation of a fire extinguishing system of the particular character described before a fusible sprinkler head opens or water damage starts, thus permitting the extinguishing 45 of the fire by such devices as are known as first aid devices.

In our prior application Serial No. 163,629, filed Jan. 26, 1927, we have shown how the opening of the main valve which is normally caused to open by the relief of pressure in the distributing piping when the 50 sprinkler head opens may be automatically advanced by utilizing the force of expansion of a heated body of confined air exposed to 55 heating in the zone protected by the sprinkler head, and in that application we show and describe the advance operation as being effected by the expansion of air normally under pressure in the main distributing piping. In our present invention we employ 60 an independent or supplemental air pipe carried from the neighborhood of the main valve to or over the area to be protected by the sprinkler head and there adapted to operate as a heat detector and air expanding device, said piping being preferably provided in such area with heating units or air containers as hereinafter more particularly 65 described. The force of expansion of the heated air acts on responsive means at the main valve to control the operation thereof and preferably through the intervention of an air valve which opens a connection for 70 air under pressure to said main valve which 75

is applied thereto in a way to cause said main valve to open. Inasmuch as said air piping is independent of the main distributing piping it is not necessary to maintain a normal air pressure therein as is required in the apparatus described in our prior application above referred to. The operating air pressure which thus causes the main valve to open is preferably derived from the main distributing pipe of the dry pipe system but might be derived from other sources without departing from our invention.

Our invention consists also in the special combinations of apparatus and details of construction more particularly hereinafter described for increasing the simplicity and effectiveness of the apparatus.

In the drawing we show in general side elevation and partial section a form of apparatus suitable for the practice of our invention.

The drawing shows a typical dry pipe sprinkler system in which 1 is the water supply, 2 is a manually operated control valve, 3 a waterway through the dry pipe valve 6 in which 4 is the water clapper that normally restrains the supply of water. 5 is an air clapper of larger size subjected to air pressure derived from the distributing system and flexibly connected to 4 for the purpose of keeping it normally on its seat. Obviously a decrease of pressure of sufficient amount upon the face of the clapper exposed to the pressure in the distributing system will permit the clapper and parts connected with it, including the main valve 4, to move and thereby open the passage for the flow of the fire extinguishing medium into the distributing system. 7 indicates a system of piping under air pressure with branch pipe 8 to which are connected thermostatically controlled automatic sprinklers 9 of the fuse controlled type shown or similar type or other outlets for the fire extinguishing medium which on being opened cause diminution of the pressure in the piping 7.

10 is a bypass pipe leading from the air pressure side of the dry pipe valve to the intermediate chamber of the dry pipe valve 23. This bypass pipe is provided with an automatic thermally operated or controlled valve 11 that normally contacts with its seat 12 and may be operated by stem 14 that passes through stuffing gland 13. 15 is a revolving weight pivoted at 15' and held in an upright position by detent 16 in contact with projecting arm 25. The detent 16 may in time of fire be pushed downward to trip the weight 15 by pressure behind diaphragm 17 which forms a flexible wall of diaphragm enclosure 18.

21 represents one or more air containers in the area to be protected and constructed preferably of good conducting material and

of large cubic capacity so as to readily increase air pressure in the piping 20 when they are heated. Pipe or tubing 20 is the pipe of the supplemental system of air piping to which is connected diaphragm 17 chamber 18. This piping or tubing contains air at normal atmospheric pressure. The tubing is preferably provided with a compensating vent 19 of such size as to dispel to the atmosphere any pressures resulting from the normal rates of rise and fall of heat in the building or area of fire protection but of such size as to not dissipate the quick or abnormal increases of pressure generated by fire conditions. The pressure of air in the piping 20 and its connections being thus modified and said piping being normally sealed excepting at the air vent 19, it is obvious that fire pressures will extend diaphragm 17 downward, rotating detent 16 around its pivot point 16', allowing weight 15 to swing to the right around its pivot point 15'. The weight, by striking the end of the valve stem 14, will force valve 11 from its seat 12 and allow the air pressure from any source but preferably from 7 to enter intermediate chamber 23 of dry pipe valve 6.

A specially designed check valve 24 serves to permit the escape of slight leakage to the atmosphere but when valve 11 is opened as above described, the rush of air forces the valve 24 against its seat and permits the same air pressure to act under disk 5 as has heretofore acted on its upper surface.

Air disk 5 being thus thrown into a balanced state, primarily through increase of temperature and pressure of air in the supplemental air piping and connections, the water pressure in 3 opens valve 4 and air clapper 5 permitting water to enter the system, forcing the air pressure into the ends of the lines and partially filling the piping system in which sprinkler heads, such as 9, may later open, discharging water practically immediately from the said sprinkler head.

The advantage of this automatic thermal valve actuator is not only in the delivery of water to the sprinkler head before the latter opens but also in enabling the dry pipe valve when it operates to sound an alarm through the alarm attachment usually provided for this type of valve. Thus an alarm would be sounded in advance of the sprinkler head operating, permitting the extinguishing of fire by such devices as are known as first-aid devices or enable the calling of the regular fire department. The alarm indicated generally at 71 may thus have a controlling switch 67 in position to be closed by the weighted lever 15 whenever the latter is released or moved to its valve actuating position as shown for example in dotted lines in the drawing. Also for the same purpose we

might employ an alarm attachment operating by a water motor to which water is admitted as soon as the main valve opens, as described in our prior application, Serial No. 103,189, filed April 20, 1926.

While we have described our automatic thermal valve actuator attached to the particular type of main dry pipe valve shown in Fig. 1, we do not, of course, wish to limit the application of our automatic thermal valve actuator to this standard dry pipe valve since, as will be readily seen by those familiar with the art, the same general principle of actuating any sprinkler system valve in advance of a sprinkler head operating can be applied to all types of such valves.

What we claim as our invention is:

1. In a fire extinguishing system, the combination with the distributing piping containing air under pressure, of a main valve normally held closed by such air pressure and controlling the admission of a fire extinguishing medium to the distributing pipes and having means unseating the same by the force of air pressure, a thermostatically controlled sprinkler head connected to the piping, a supplemental piping containing air, a valve controlling the passage of the unseating air pressure to said main valve and means controlled by the increase of air pressure in said supplemental piping resulting from fire conditions in the area to be protected by the sprinkler head for bringing the last-named valve into action.

2. In a fire extinguishing system, the combination of a main piping containing a fluid under pressure, a valve controlling the supply of the extinguishing medium to the piping and normally maintained in closed position by the pressure of the fluid in said piping but adapted to open on decrease of said pressure, a thermostatically controlled sprinkler head connected to the piping, a supplemental sensitive thermostat acting more promptly than the sprinkler head and consisting of a system of fluid containing piping independent of the main piping so as to be unaffected by changes of pressure in said main piping and means responsive to increase of fluid pressure in said supplemental system of piping due to increase of temperature adjacent said sprinkler head for applying to said valve a force acting positively on the same to unseat it against the pressure tending to maintain it closed.

3. In a fire extinguishing system, a distributing pipe for the fire extinguishing medium, a differential automatic main valve, held normally closed by the pressure of fluid in the distributing pipe and adapted to open by the relief of said pressure, automatic sprinkler heads connected to said pipe, a supplemental system of air piping extending from the main valve to the area to be protected and means subject to the pressure of

air in said supplemental piping for automatically admitting fluid under pressure to a valve chamber wherein such pressure tends to unseat the main valve upon increase of air pressure in the supplemental system due to increase of temperature in the area protected by a sprinkler head, said increase being effective on the main valve in advance of the action of the sprinkler head.

4. In a fire extinguishing system, a distributing pipe for the fire extinguishing medium, a differential automatic main valve, held normally closed by the pressure of air in the distributing pipe, a thermostatically controlled outlet connected to said pipe, a supplemental system of air piping extended from the zone protected by said outlet to the location of the main valve and having a restricted compensating air vent and containing air at normal atmospheric pressure, a chamber adapted to receive and apply unseating fluid under pressure for causing the main valve to open against the normal pressure of air in the distributing piping and means for automatically admitting fluid under pressure thereto controlled by an increase of air pressure in the supplemental system of piping, which is not compensated by said vent, said means normally acting to admit fluid under pressure to the chamber in advance of the thermostatic operation of the outlet.

5. In a thermostatically controlled automatic fire extinguishing system, the combination with a distributing main containing air under pressure and provided with a normally closed fire extinguishing outlet, a thermostat for causing said outlet to open on a predetermined increase of temperature for discharging the extinguishing fluid, a valve controlling the supply of the extinguishing medium to the distributing main normally held closed by the normal pressure in the distributing main but adapted to open automatically upon decrease of said pressure produced by the opening of an outlet, of a supplemental air piping, pressure producing means connected therewith and located in the fire zone protected by said outlet, an air vent for modifying small changes in pressure in said air piping, and means connected with said supplemental piping and responsive to a substantial increase of air pressure therein for normally causing the application of an unseating force to said valve before any substantial decrease in pressure in said distributing main may occur.

6. In a fire extinguishing system, the combination with distributing piping for the fire extinguishing medium, a thermostatically controlled outlet connected thereto, a controlling valve controlling the supply of fire extinguishing medium to the piping and automatically responsive to a decrease of the normally maintained fluid pressure in said

piping due to an opening of an outlet by increase of temperature, a supplemental system of air piping independent of the distributing piping, an air container located in the 5 heating zone of said outlet, connected with the supplemental piping, a restricted outlet for said supplemental piping for modifying the rate of rise of pressure therein and means responsive to increase of pressure at a greater 10 than the adjusted rate for causing fluid pressure to be applied to operate the said control valve in advance of the operation of the thermostatically controlled outlet and means 15 for unseating said valve through the action of said admitted air pressure.

7. In a fire extinguishing system, the combination with a distributing piping normally containing air under pressure and a valve for causing a supply of fire extinguishing medium 20 to flow thereto, said valve being normally held closed by the air pressure in said piping, thermostatically controlled means for releasing said air pressure and means for operating said valve in advance of the action 25 of said thermostatically controlled releasing means, said operating means comprising a separate system of piping containing air subject to heating in the zone protected through 30 said piping and connected to means responsive to increase in pressure therein, a control valve controlling the application of an unseating fluid pressure to the first-named valve, a trip device actuated by said responsive means and means controlled by said trip 35 device for operating said control valve.

8. In a dry pipe fire extinguishing system having a main piping containing air under pressure, the combination with thermostatic means for releasing said air pressure, a main valve normally maintained in closed position by air pressure in the main piping acting against the valve unseating influence of the fire extinguishing fluid supply, a supplemental system of air piping outside 40 the main piping and containing air subject to increase the pressure by heating in the zone of said thermostatic releasing means and means controlled by increase of air pressure in the latter for admitting an unseating air pressure from the main pipe to a chamber 45 wherein it may act on the main valve in a direction to unseat the same and in advance of the action of said thermostatic releasing means.

55 9. In a fire extinguishing system, the combination of a dry pipe system of piping, a valve controlling the flow of fire extinguishing medium to said piping and normally held in closed position by the air pressure in 60 said piping acting in opposition to the pressure of said medium upon the valve, means for causing said valve to open by an unseating pressure applied thereto in opposition to the seating pressure and normally inactive, 65 thermostatic means for releasing the air

pressure in the piping and means for operating said valve in advance of the action of the air releasing means, said means comprising a supplemental system of air piping containing air at normal atmospheric pressure 70 and increasing in pressure by independent thermostatic action in the heat zone of the thermostatic air releasing means and independent of piping of the dry-pipe system and means controlled by increase of pressure 75 in said supplemental air piping for applying the unseating pressure to the control valve for the fire extinguishing medium.

10. In a dry pipe fire extinguishing system, the combination with a control valve controlling the supply of fire extinguishing medium to the system and normally maintained in closed position by the pressure of fluid in the system but adapted to open automatically upon decrease of the fluid pressure therein 80 thermo-responsive means in the fire zone for automatically decreasing said pressure, a supplemental system of air piping extending from the area to be protected to the control valve, means for causing the main valve 85 to be unseated by the application of fluid under pressure operating in opposition to the pressure acting to normally maintain the valve closed, a valve controlling the passage 90 of the unseating fluid and means for bringing the latter valve into operation through the expansion of air in said supplemental system produced by heat in the fire zone 95 wherein the said thermo-responsive means are located.

11. In a dry pipe fire extinguishing system, the combination with a control valve controlling the supply of fire extinguishing medium to the system and normally maintained in closed position by the pressure of fluid in the system but adapted to open automatically upon decrease of the fluid pressure therein, thermo-responsive means in the fire zone for automatically decreasing said 105 pressure, a supplemental system of air piping extending from the area to be protected to the control valve, and means for causing said valve to open by application of unseating pressure of fluid applied to the main valve in opposition to the pressure tending 110 to hold the same closed and admitted thereto by the controlling action of the pressure of air heated in said supplemental system in the fire area wherein said thermo-responsive means are located.

12. In a fire extinguishing system having a main piping containing fluid under pressure, the combination with thermostatic means for releasing said pressure, a main valve formed with a chamber for receiving 125 unseating fluid under pressure and normally maintained in closed position by the pressure in the main piping acting against the valve unseating influence of the fire extinguishing fluid supply, a supplemental sys- 130

tem of piping independent of the main piping and containing air subject to increase of pressure by heat in the zone of said thermostatic releasing means and means controlled by increase of air pressure in said supplemental system for admitting unseating fluid under pressure to said chamber of the main valve for action thereon in a direction to unseat the same in advance of the action of said thermostatic releasing means.

10 Signed at Cleveland, in the county of Cuyahoga and State of Ohio, this 5th day of February, A. D. 1927.

ERNEST A. LOWE.
JOHN R. HAMILTON.
